UNITED STATES PATENT OFFICE.

VALENTINE C. LUPPERT, OF WILLIAMSPORT, PENNSYLVANIA.

STOP-SECURING MACHINE.

1,125,574.

Specification of Letters Patent.

Patented Jan. 19, 1915.

Application filed June 6, 1914. Serial No. 843,483.

To all whom it may concern:

Be it known that I, VALENTINE C. LUPPERT, of Williamsport, in the county of Lycoming and State of Pennsylvania, have invented certain new and useful Improvements in Stop-Securing Machines; and I do hereby declare the following to be a full, clear, and exact description of the invention, such as will enable others skilled in the art to which it appertains to make and use the same.

This invention relates to improvements in machines for securing drawer stops to the rails or sills of furniture,—one object of the invention being to provide simple and efficient means for accurately placing and securing drawer stops to rails or sills before the latter shall have been built into the furniture.

A further object is to provide means for applying and securing drawer stops, in which the stop may be previously assembled in portable receptacles which may be inserted into the magazine portion of the machine and fed therefrom, one at a time, to the driving means, each of said receptacles constituting, when in place in the machine, a removable lining for the magazine.

A further object is to so construct and mount the magazine that it may be removable to facilitate the insertion of a receptacle containing the stops, and in which said receptacle may be supported in such manner as not to interfere with the accurate feeding of the stops therefrom.

A further object is to provide simple and efficient adjustable means for regulating the proper spacing of the stops from the edge of the rail or sill.

With these and other objects in view, the invention consists in certain novel features of construction and combinations of parts as hereinafter set forth and pointed out in the claims.

In the accompanying drawings; Figure 1 is a side elevation partly in section of a machine embodying my improvements; Fig. 2 is a section on the line 2—2 of Fig. 1; Fig. 3 is a section on the line 3—3 of Fig. 1; Fig. 4 is a section on the line 4—4 of Fig. 1; Fig. 5 is a plan view with the magazine removed; Fig. 6 is a detail view showing the magazine, and Figs. 7 and 8 are views of certain details.

1 represents a frame upon which a metal platform 2 is rigidly secured.

Two parallel standards 3—3 project upwardly from the platform and are suitably spaced apart to form guideways for a reciprocating head 4, said standards being 60 made on their inner sides with elongated shoulders 5 on which the head 4 may slide. The upper face of the head 4 is recessed to receive the butt end portion of a driver plate 6, the latter having a recessed free end 65 to conform approximately to the external shape of the drawer stops to be driven into the rails or sills. Guide plates 7, 7, are secured upon the standards 3 and overlie the head 4 and driver plate 6. 70

A block 8 is located forwardly of the standards 3 so as to be disposed in front of the space between the standards, said block being provided at its base with lateral projections secured to the platform 2. The 75 block 8 is so disposed that when the driver plate is projected, the latter will move over the upper face of said block. At its side edges, the block 8 is made with ledges 9 which are undercut to form guide-ways for 80 the side edges of the driver plate.

Uprights 10, 11 are secured to the sides of the block 8 and project above the same, the portions of said uprights being provided, respectively, with inwardly projecting flanges 12 and thus constitute a holder for a magazine 13. The rear flanges of the uprights terminate at their lower ends slightly above the upper face of the block 8 and serve to assist in guiding the driver 90 plate. The forward edges of the uprights and their flanges are notched to receive the ends of a cross bar 14,—the latter being spaced slightly from the upper face of the block 8 to form a discharge slot 14^a for stops 95 15. The cross bar 14 may be provided with a notch 16 for a purpose hereinafter explained.

The magazine 13 may be conveniently made of sheet metal bent to form a rectangular receptacle having an elongated opening 16^a in its front, and the upper end of the magazine will preferably be provided with inwardly projecting flanges 17. The magazine will be held removably in the holder 100 formed by the uprights 10—11 by means of a spring-pressed latch 18 mounted in the upright 10 and adapted to engage in a hole in the lower portion of one side wall of the magazine. The stops 15 are contained in 110 an elongated receptacle 19 which may be made of pasteboard and may be packed at

the source of supply of stops, the receptacles 19 may be provided with removable covers to facilitate handling and transportation, but when the stops are to be supplied to the machine, the cover of a receptacle will be removed and one end of said receptacle will also be removed. The magazine will be removed from the holder and the receptacle containing the stops will be inserted bodily into the magazine through the lower end of the latter. In order to prevent escape of the stops while the magazine is being placed into its holder, a pin may be passed through alining holes in the lower portion of the magazine, the front end of said pin entering the notch 16 in the cross bar 14. After the magazine shall have been inserted into its holder, the pin may be withdrawn. When the magazine is in place in the holder, its lower end will rest upon the ledges, and the lower end of the receptacle 19 (which latter forms a temporary lining for the magazine) also rests upon said ledges 9. Thus it will be seen that when the magazine is supplied with a receptacle containing a number of superimposed stops, shall have been applied to the machine as above described, the lowermost stop 15 will rest upon the upper face of the block in line with the driver 6 so as to be projected through the discharge opening 14^a when said driver is moved forwardly.

An upright bracket 20 is located on the platform 2 and spaced from the block 8 and if desired, this bracket may be made integral with the platform. Pins 21 project inwardly from the lower portion of the bracket 20 and upon these pins a shoe 22 is supported. This shoe may be faced with a wooden strip 23 (preferably having a curved upper face) to receive and support a rail or sill into which the stops are to be driven,—said rail or sill being inserted between the block 8 and the bracket 20 so that the latter will form a driving abutment. The end portions of the shoe are made with beveled or cam faces which engage the pins 21 so that when the shoe is moved endwise, it will be raised or lowered so that it may be adjusted to regulate the distance from the edge of the rail or sill at which it may be desired to locate the stops. The bracket 20 is made with an inclined slot 24 through which a screw 25 passes and engages in a threaded socket in the shoe. By these means, the shoe may be secured at any desired adjustment.

For the purpose of operating the driver, the devices now to be described are employed.

One member of a toggle lever 26 is pivotally connected to the sliding head 4 of the driver and the other member of said toggle lever is pivoted to fixed lugs 27 on the plat-

form. A coupling 28 is pivotally attached to the toggle lever at the pivotal juncture of its two members and depends therefrom. A rod 29 is secured to the coupling 28 and extends downwardly through an opening 30 in the platform 2, the lower end of said rod being connected with a treadle 31 mounted in the lower portion of the framework 1. This treadle and the parts with which it is connected is maintained in and returned to normal positions, by means of a spring 31^a, one end of which is attached to the treadle and the other end to the frame 1.

It is apparent that when a rail or sill is placed in position between the block 8 and the bracket 20 and the treadle is depressed the driver will be moved forwardly and a stop will be driven accurately into the rail or sill.

In order to provide a stop for the operating mechanism and to regulate the throw of the toggle lever and the sliding head of the driver, an adjustable screw 32 is located upon the platform 2 in position to be engaged by the coupling 28 when the toggle is in elevated position and the driver be engaged by the coupling 28 when the driver is withdrawn,—said screw also being positioned to be engaged by one member of the toggle when the latter is in its lower position and the driver is projected. It is apparent that by adjusting the screw 32, the throw of the driver may be accurately adjusted.

Having fully described my invention what I claim as new and desire to secure by Letters-Patent, is:—

1. In a machine of the character described, the combination with a horizontally movable driver, means for supporting the same, and means for reciprocating said driver, of a fixed bracket in front of the driver and having an inclined slot, pins projecting from said bracket, a shoe disposed between the driver support and said bracket for supporting a rail to receive stops, said shoe having inclined faces to engage said pins, and a screw engaging said shoe and movable in the inclined slot in the bracket.

2. In a machine of the character described, the combination with a frame and a platform mounted on said frame, of driving means mounted on said platform, a toggle lever connected with the driving means and with the platform, a pedal, means connecting said pedal with the toggle lever, and an adjustable stop on the platform in position to be engaged by said connecting means and by said toggle lever to control the stroke of the driving means.

3. In a machine of the character described, the combination with a platform, guides thereon and a bracket on said platform in front of and spaced from the guides, of a

block in front of said guides and having ledges at its sides, a head movable in said guides, a driver carried by said head and movable over the block and between said ledges, a magazine holder secured to said block, and a removable magazine mounted in said holder and adapted to rest upon the ledges at the sides of said block.

4. The combination with a stop setting mechanism, of a removable magazine, and a removable receptacle constituting storage means for stops and a lining in said magazine.

5. The combination in stop setting means, 15 of a removable magazine comprising a metal container, a removable storage container for insertion into the metal container, and

means for holding the magazine in feeding position on the machine.

6. In a machine of the character described, the combination with setting mechanism, of flanged standards constituting a magazine holder, a magazine mounted in said holder, means for locking said magazine in place, and a removable storage receptacle constituting a lining in said magazine.

In testimony whereof, I have signed this specification in the presence of two subscribing witnesses.

VALENTINE C. LUPPERT.
